UNITED STATES PATENT OFFICE.

ALMA M. ROSE, OF NEW YORK, N. Y.

DISPENSING APPARATUS FOR COOLED LIQUIDS.

1,050,233.

Specification of Letters Patent. Patented Jan. 14, 1913.

Application filed May 26, 1911. Serial No. 629,536.

To all whom it may concern:

Be it known that I, ALMA M. Rose, a citizen of the United States, residing at New York, in the county of New York and State 5 of New York, have invented certain new and useful Improvements in Dispensing Apparatus for Cooled Liquids, of which the following is a specification.

My present invention pertains to an im- 10 proved dispensing apparatus for cooled liquids, the construction and advantages of which will be hereinafter set forth, reference being had to the annexed drawing, in which the apparatus is shown in vertical 15 section.

In dispensing certain liquids, such for instance as fruit juices and the like, it is essential that the liquid be kept out of contact with the gaskets employed in the appa- 20 ratus, and particularly where the gaskets are made of rubber, as the acid of the fruit juices attacks the rubber, rendering it use- 25 less in a relatively short time, and likewise imparting a disagreeable taste to the liquid, which is a matter of more serious moment.

The main object of the present invention is to produce a dispensing apparatus wherein the liquid will be automatically kept out 30 of contact with the gasket, and a tight joint will be likewise effected between the gasket and the liquid-container.

A still further object of the invention is to provide a simple and strong apparatus, one which may be shipped from the factory 35 fully assembled, so that the purchaser or user is under no necessity of doing anything but place a container in operative position on the cooler proper, and then fill it with the liquid to be dispensed. In other 40 words, the construction is such that once being tested out before shipment no further work is necessary, and the user may readily effect the positioning of the liquid container.

In the drawing, 1 denotes the main body 45 of the receptacle, adapted to contain the ice, which may be introduced through the opening which is usually closed by the cover or lid 2. Resting upon the bottom of the 50 receptacle is a cooler 3, comprising a hollow body having a tortuous passage there- 55 through to which is connected a pipe 4 which, in turn, leads to a faucet 5. A vertically-disposed pipe 6 is connected to the inner end of the passage in the cooler 3, the upper end of said pipe being secured

to and opening into the lower end of a cup-shaped member 7. The lower portion of said member is of a diameter smaller than the upper section, an inwardly-projecting ledge or shoulder 8 being thereby formed, which affords a seat for a continuous ring-shaped gasket 9, preferably formed of rubber. The upper end of the cup-shaped member is turned outwardly and finds its 60 seat or bearing upon the curved flange 10 formed at the upper end of a collar 11, extending upwardly from the top 12 of the receptacle. A buffer ring 13 is seated in the curved flange and serves in a measure 65 to steady the liquid-containing receptacle.

The container, which in the present instance is shown as being made of glass, is provided with a body portion 14, having an opening at its upper end which is closed by 70 a lid or cover 15. Extending from the lower end of the container is a relatively 75 long, tapering nozzle 16 adapted, when the parts are positioned, to make a wedging fit with the gasket 9, said nozzle extending 80 through said gasket and well down into the lower portion of the cup-shaped member.

It is thought that the operation of the apparatus will be clearly understood upon reference to the drawing.

The container is placed in position as shown, with the neck passing through the gasket, and by reason of the weight of the container and the tapering form of the nozzle, a tight joint is effected with the gasket, 90 preventing the leakage of air past the same, whereby a portion of the air which is in the cooler, the pipe 6, and the cup-shaped member will be pocketed below the gasket and the liquid will be prevented thereby from 95 passing upwardly into contact with the gasket, a point of manifest advantage, especially where the liquid being dispensed is acid in its nature and would tend to affect the rubber and likewise be affected thereby.

The buffer ring 13 serves the purpose of preventing contact of the lower end of the nozzle with the metallic portions of the structure when the container is being positioned, and furthermore serves in a measure to prevent undue displacement of the container with reference to the gasket after the parts are positioned. It will be noted, however, that the nozzle does not normally contact with the buffer ring 13, but that the 100 weight of the container is transmitted directly to the gasket 9, thereby effecting and

maintaining a tight joint at this point at all times.

Having thus described my invention, what I claim is:

- 5 1. In a liquid-cooler, the combination of a receptacle adapted to hold a refrigerant; a top provided with an upstanding collar; an outwardly-curved flange formed at the upper end of the collar; an open cup-shaped member mounted within and supported by said collar, the upper end of said member being turned outwardly and fitting the curved flange aforesaid; a buffer-ring carried by said out-turned end; an inwardly-projecting ledge formed within the cup; a ring-shaped gasket seated upon the ledge; a cooler for the liquid to be dispensed connected to the lower end of the cup-shaped member; and a liquid-container provided with a relatively long tapering nozzle adapted to pass through and make a tight joint with the gasket.
- 10 2. In a liquid-cooler, the combination of a receptacle adapted to hold a refrigerant; a hollow body mounted therein and through which the liquid to be dispensed passes; a cup-shaped member mounted in the upper portion of the receptacle and communicating at its lower end with the hollow body; a gasket mounted within and supported by the cup-shaped member at a point remote from its upper end; and a liquid-container or jar provided with a relatively long, tapering nozzle adapted to pass into the cup-shaped member and through the gasket to make a wedging joint therewith, whereby the liquid will be prevented from passing upwardly into contact with the gasket by the air trapped within the cup-shaped member below the gasket.
- 15 3. In a liquid-cooler, the combination of a receptacle adapted to hold a refrigerant; a hollow body mounted therein and through which the liquid to be dispensed passes; a cup-shaped member mounted in the upper portion of the receptacle and opening at its lower end into the hollow body, said cup-shaped member being provided with a ledge or shoulder between its upper and lower ends; a continuous ring-shaped gasket mounted upon said shoulder; and a liquid-container or jar provided with a relatively long, tapering nozzle adapted to pass into

the cup-shaped member and through the gasket to make a wedging joint therewith, whereby the liquid will be prevented from passing upwardly into contact with the gasket by the air trapped within the cup-shaped member below the gasket, and the gasket will be supported at a point remote of access.

4. In a liquid-cooler, the combination of a receptacle adapted to hold a refrigerant; a hollow body mounted therein and through which the liquid to be dispensed passes; a cup-shaped member mounted within an opening formed in the top of the receptacle, and partially supported by said top, the cup-shaped member being provided with an inwardly-extending flange; a pipe extending from the lower portion of the cup-shaped member to the hollow body; a continuous ring-shaped gasket mounted on the flange aforesaid; a buffer ring mounted at the upper portion of the cup-shaped member; and a receptacle for the liquid to be dispensed, said receptacle being provided with a relatively long, tapering nozzle, adapted to be passed into the cup-shaped member and through the gasket, making a tight joint with the gasket, whereby the air pocketed within the cup-shaped member below the gasket will prevent the liquid from passing upwardly into contact with the gasket.

5. In a liquid-cooler, the combination of a receptacle to contain a refrigerant; a cooler located therein; an open, cup-shaped member secured in the top of the receptacle; a gasket mounted within the cup-shaped member and supported thereby; a buffer ring located at the upper end of the cup-shaped member; and a liquid-container having a depending tapering nozzle adapted to pass through the gasket and to make a tight fit therewith, the lower end of the nozzle terminating at a point below the gasket, whereby an air pocket will be formed around the nozzle below the gasket.

In testimony whereof I have signed my name to this specification in the presence of two subscribing witnesses.

ALMA M. ROSE.
